FIREWORKS

Louis L. Driggs, Jr., Tippecanoe City, Ohio, assignor to The Tipp Fireworks Company, Tippecanoe City, Ohio, a Corporation of Ohio

Application November 27, 1931
Serial No. 577,413

11 Claims. (Cl. 102—21)

My invention relates to fireworks.

It is the object of my invention to provide a fireworks article of manufacture which can be completely assembled at the factory and shipped as a complete unit.

It is my object to provide a fireworks display article which will entertain by first having the explosion on the ground in the course of firing a projectile into the air; second, as the projectile rises in the air, it will discharge a fireworks display until the time fuse in the projectile ignites the contents of the projectile, such as star shells, whereupon the contents of the projectile will be blown out, making the final fireworks display from 100 to 200 feet in the air where it will not be dangerous and its full beauty can be seen.

In a fireworks article such as this there are several essential requirements which this invention fulfills that are new in combination in this 20 art with the type of construction as indicated herein:

First, the construction is completely assembled at the factory so that the user cannot modify the construction or make it dangerous.

Second, only a single shell is used in a single mortar, thereby avoiding premature explosion of shells or projectiles which are fired from the same mortar in succession.

Third, the projectile itself serves as the cover 30 for the lifting or elevating charge.

Fourth, the projectile completely closes the interior of the mortar so that the full effect of the gases will be had upon the base of the projectile and will elevate the projectile uniformly when 35 using a uniform charge of powder so that uniformity of results can be secured and there will be no jamming of the projectile in the mortar.

Fifth, the fuse with which the explosions are initiated extends through the bottom side wall of 40 the mortar so that the person operating the mortar need not place himself over the top of the mortar, so that this fireworks is entirely safe for a child to operate.

Sixth, the projectile provides a continuous display from the ground until it gets to the maximum height.

Seventh, the pyrotechnic material which is burning during the flight of the projectile cannot get around the plug holding the time fuse and 50 prematurely ignite the contents of the projectile, as a guard, such as a metal cap, is provided to prevent such fire leakage, or a pressed clay plug.

Eighth, the retaining plug carrying the time fuse is completely blown out so that an even discharge of the contents of the projectile is made.

Ninth, the projectile is usually blown to pieces so that only harmless fragments fall.

Referring to the drawings, Figure 1 is a side elevation of the mortar.

Figure 2 is a section through the mortar and 60 projectile.

Figure 3 is a section through the projectile after the pyrotechnic display in the mortar or projectile has been substantially completely fired and the time fuse is nearly completely consumed. 65

Figure 4 indicates the form of the projectile after its contents have been blown out.

Figure 5 shows the plug in section, which could be of wood or clay, or other material.

Figure 6 shows the safety cap in section.

Figure 7 is a top plane view of the mortar with the shell in place.

Figure 8 is a section through the projectile showing the discharge of the stars at the top of the flight of the projectile in the form in which 75 the projectile is not ruptured.

Figure 9 is a section through the mortar and projectile before firing showing the form using the pressed clay head to the projectile instead of the wooden plug and metal cap.

Figure 10 is a diagrammatic view showing the projectile in flight with the pyrotechnic display burning at its base during the flight and showing its final position in which the entire projectile is ruptured and the pyrotechnic stars are driven 80 in all directions.

Figure 11 is a bottom plan view of the projectile with the clay plug.

Referring to the drawings in detail, 1 is the base of the mortar having the mortar 2. The base may be of wood and the mortar can be of cardboard, although any suitable materials may be employed if they are light and cheap as they are to be used for a purely fireworks item.

The mortar tube 2 is countersunk as at 3 within the base 1. Within the interior of the mortar is placed a lifting charge 4 which is ignited by the fuse 5 extending through the side wall of the mortar 2 at the bottom thereof.

The projectile comprises a cardboard casing 6 having a metallic end closure 7 at the top. The projectile is filled with any pyrotechnic material such as stars 8, powder 9 and pieces of quick match 10. The fuse plug of wood or clay or other suitable material designated 11 is then inserted within the open mouth of the projectile 6 so that the shoulder 12 of the plug engages the end 13 of the side wall 6 of the projectile. This places the overhanging side wall 14 of the plug in substantial alignment with the outside side wall 6.

100
105
110

of the projectile. The interior of the plug is provided with a pyrotechnic display chamber 15 and a time fuse passageway 16. The pyrotechnic display chamber is filled with a pyrotechnic display which burns on the flight of the projectile upwardly, such display being designated 17.

Over this end of the projectile and the fuse plug is mounted a metallic cap 18 which has its side walls pressed into the cardboard side walls 6 of the projectile to form a tight seal with it so it is impossible for fire to creep between the plug 11 and the side wall 6 to prematurely ignite the contents of the projectile.

It will be understood that I desire to comprehend within my invention such modifications as may be necessary to adapt it to varying conditions and uses.

It will be further understood that my mortar takes the place of rockets, which are dangerous because of the falling of the stick, whereas the projectile casing of my invention is so very light that even if it should fall and strike anyone, it would not injure them.

My projectile has all the advantages of a rocket as the projectile has a continuous illuminated discharge during its flight, terminating in a burst of stars.

In Figure 8 is shown one form of discharge, that is, through the end of the projectile when it is desired to concentrate the discharge in a stream, while Figure 10 shows the form in which the projectile is completely ruptured and the stars are blown in all directions to make a grand display.

In Figures 9 and 11 there is shown a modification of the projectile in which a clay base 11 is employed in the place of the wooden plug and the metal cover. The clay is pressed in under heavy pressure so that it can be with difficulty blown out. It prevents any leakage of fire between the clay and projectile side wall 6 and upon the explosion of the powder 9, the side walls of the projectile will be ruptured. Either construction may be employed without departing from the sense of my invention.

Having thus fully described my invention, what I claim as new and desire to secure by Letters Patent, is:

1. In combination, a mortar, a lifting charge in the base thereof, a fuse extending from the exterior of the mortar into the interior thereof in said lifting charge, a projectile resting on said lifting charge fitting within said mortar, a fuse plug in the projectile having a display chamber and a passageway, a time fuse in said passageway ignited by the lifting charge, a display material in the chamber, and pyrotechnic contents in the projectile.

2. In combination, a mortar, a lifting charge in the base thereof, a fuse extending from the exterior of the mortar into the interior thereof in said lifting charge, a projectile resting on said lifting charge fitting within said mortar, a time fuse in said projectile ignited by the lifting charge, and pyrotechnic contents in the projectile, and supplementary pyrotechnic contents interposed between said time fuse and the lifting charge adapted to be fired as the projectile proceeds on its flight from the mortar.

3. In combination in a shell for firing from a mortar for fireworks display, a projectile casing having an open bottom and a side wall, a fuse plug mounted in the bottom, a time fuse and a display material in said plug, and a sealing means enclosing said plug and one end of said projectile.

4. In a projectile for use in a fireworks mortar comprising a side wall and a closed end, a detachable plug adapted to be blown out by the contents of the projectile, having a shoulder thereon for engaging the end of the side wall of the projectile, said plug having a time fuse passageway and a pyrotechnic containing chamber therein.

5. In a projectile for use in a fireworks mortar comprising a side wall and a closed end, a detachable plug adapted to be blown out by the contents of the projectile, having a shoulder thereon for engaging the end of the side wall of the projectile, said plug having a time fuse passageway and a pyrotechnic containing chamber therein, and a safety cup enclosing the outer end of said plug and overlapping the adjacent end of the projectile, said cup having an aperture for the discharge therethrough of the contents of the pyrotechnic chamber in the plug.

6. In combination, a projectile comprising a side wall, a permanent end wall, a detachable end wall comprising a chambered plug having a reduced part fitting in the side wall and a part in line with the outer surface of the side wall adapted to be blown out by the contents of the projectile, and a metallic safety cup having an aperture coinciding with the chamber in the plug and adapted to overlap the exposed end of the plug and the adjacent end of the projectile.

7. In a fireworks display apparatus, a mortar, a lifting charge, a fuse therein extending through the side wall of the mortar, a projectile having a plug in the mortar, said projectile having pyrotechnic contents, said plug having a chamber and passageway for pyrotechnic material and a time fuse, and pyrotechnic material and a time fuse therein.

8. In a fireworks display apparatus, a mortar, a lifting charge, a fuse therein extending through the side wall of the mortar, a projectile having a plug in the mortar, said projectile having pyrotechnic contents, said plug having a chamber and passageway for pyrotechnic material and a time fuse, and pyrotechnic material and a time fuse therein, said time fuse passageway being of restricted diameter as compared with the projectile chamber in the plug.

9. In combination, a mortar, a projectile having in one end a plug with a chamber therein, means of firing the projectile from the mortar, and means in the chamber for delivering a continuous pyrotechnic display during the projectile flight and means at the end of the flight of providing a grand pyrotechnic display upon the discharge of the projectile contents.

10. In combination, a mortar, a projectile having in one end a plug with a chamber therein, means of firing the projectile and of igniting the contents of the chamber, means in the projectile for providing a support for a pyrotechnic display during the flight of the projectile and additional pyrotechnic means in the projectile ignited by the last mentioned means at the end of the flight of the projectile for the discharge of the final pyrotechnic display.

11. In a fireworks item, a mortar having a lifting charge and fuse, a projectile therein comprising a side wall that can be ruptured by an explosion, a pressed clay cup closing one end thereof containing a time fuse and a pyrotechnic material, and a pyrotechnic contents within said projectile adapted to be fired by said time fuse.

LOUIS L. DRIGGS, JR.
